CLAIM

The ornamental design for a modular portable outhouse, as shown and described.

DESCRIPTION

FIG. 1 is a profile perspective view taken from the front and left side and above of a modular portable outhouse showing our new design;

FIG. 2 is a front elevation view thereof;

FIG. 3 is a top plan view thereof;

FIG. 4 is a rear elevation view thereof;

FIG. 5 is a bottom plan view thereof;

FIG. 6 is a right side elevation view thereof; and,

FIG. 7 is a left side view thereof.
